WASHING MACHINE

Hessie T. Rutherford, Kansas City, Mo.

Application April 1, 1933. Serial No. 663,998

12 Claims. (Cl. 68—18)

This invention relates to a washing machine, and has for its primary object to so construct and arrange the elements therefor, in a manner as hereinafter set forth to provide for expeditiously and thoroughly washing articles formed from textile material, but it is to be understood that a washing machine in accordance with this invention is designed for washing any type of article for which it is found applicable.

10 A further object of the invention is to provide, in a manner as hereinafter set forth, a machine of the class referred to including a revoluble skeleton cylinder having means for securing thereto, the articles to be washed in fixed suspended parts 15 allel relation during the revolving of the cylinder whereby each suspended article will be individually washed.

A further object of the invention is to provide, in a manner as hereinafter set forth, a washing machine including a tank for containing a body of water and a clockwise and counter-clockwise revoluble skeleton cylinder suspended in the tank in spaced relation with respect to the bottom of the latter and with the cylinder having means 25 for removably suspending from the outside thereof, each individual piece of laundry to be washed to provide, during the revolving of the cylinder, for the laundry to be forced with great resistance through the water resulting in each piece of laundry 30 dry attached to the cylinder to be thoroughly washed individually.

Further objects of the invention are to provide, in a manner as hereinafter set forth, a machine of the class referred to which is simple in its construction and arrangement, strong, durable, compact, thoroughly efficient in its use, expeditious in its action, readily assembled, permitting of the articles to be washed to be conveniently attached thereto, and comparatively inexpensive to manufacture.

To the above ends essentially and to others which may hereinafter appear, the invention consists of such parts and such combination of parts which fall within the scope of the invention as claimed.

The machine includes an operating element comprising a clockwise and counter-clockwise driven shaft carrying the skeleton cylinder and which may be revolved from any suitable means, 50 i. e., a motor or hand power, and such means is illustrated by way of example as a manually shifted crank handle attached to one end of the cylinder carrying shaft.

In the drawings wherein like reference characters denote corresponding parts throughout the several views:—

Figure 1 is a perspective view of the washing machine when closed.

Figure 2 is a vertical sectional view of the washing machine when opened.

Figure 3 is an elevation of the tank looking towards the rear side thereof.

Figure 4 is a cross sectional view of the skeleton cylinder which provides a carrier for the articles to be washed.

65

Figure 5 is a perspective view of the skeleton cylinder.

Figure 6 is a perspective view of the form of combined grip and agitator.

The machine includes an open top and closed bottom tank 1 for containing a body of water. The tank may be of any suitable contour in plan, preferably square and is so shown. The front and rear walls of tank 1 are designated 2, 3 respectively, the side walls at 4, 5 and the bottom 75 at 6. The tank 1 is set up with an upper portion 7 and a lower portion 8. The portion 7 is of greater height and area than portion 8, and the latter flares from bottom 6 to its point of merger with portion 7. The setting up of portion 80 8 in the manner referred to provides the tank with a lower part of substantially inverted frusto-conoidal contour. The portion 7 is also flared, but the flare thereof is less than the flare of portion 8. The bottom 6 is of an area materially 85 less than that of the open top of the tank.

The top of each of the walls of the tank is provided with an outwardly directed lip 9 of angle-shape cross section to form a combined internal seat and abutment for the edges of a hinged lid 90 or closure 10. The lips 9 at the ends thereof merge into each other.

Formed integral with the inner face of the lip 9 of wall 4 is a pair of upstanding inwardly inclined spaced parallel apertured hinge members 95 11 between which is arranged an apertured hinge member 12 extended from the outer face of lid 10 adjacent one side edge thereof. The member 12 is pivoted to members 11, as at 13 and by this arrangement the lid 10 is hinged with one side of tank 1. The lid 10 adjacent its other side edge has extended outwardly therefrom a knob 14 to facilitate the swinging of the lid to and from closure position with respect to the open top of the tank. When the lid 10 is closed it 105 swings under members 11 and its edges bear against the combined seat and abutment provided by each lip 9 below the top edge of the latter. The outer face of lid 10 is inset to provide a pocket 15 for a purpose to be referred to.

The walls 4, 5 of tank 1 in proximity to bottom 6 has depending therefrom a pair of spaced apertured lugs 16. The tank 1 is supported upon two pair of upwardly extending spaced legs 17. The legs of each pair extend inwardly at an inclination from their lower ends. Each leg at its upper end overlaps a lug 16 and is apertured. The apertures of the legs align with the apertures of the lugs. The legs and lugs are secured together 115 120

by holdfast means 18 extending through the aligning apertures.

Pivotaly connected as at 19 to the outer face of wall 4 is the lower end of a supporting rod 20, 5 and the latter is adapted to have its upper end removably extended into the pocket 15 for supporting the lid 10 when swung to open position with respect to the top of tank 1, Figure 2.

The wall 2 of tank 1 in proximity to bottom 6 10 has attached thereto a drain cock 21. The portion 7 in proximity to and below its horizontal median is provided with a pair of opposed openings, 22, 23, and the said openings are formed in walls 4, 5. Threadedly engaging with the wall of opening 22 is a bearing sleeve 24 which extends from wall 4 into the tank 1. The sleeve 24 is of uniform diameter throughout. Extending through wall 5 into the tank 1 is a tubular member formed of two parts of different diameter. The part of 15 smallest diameter, indicated at 25 threadedly engages with the wall of opening 23, extends inwardly from wall 5 and constitutes a bearing. The other part of the tubular member, which is indicated at 26, provides a gland for a packing 27. Threadedly engaging with the inner face of part 26 and bearing against the packing 27 is a flanged collar 28.

Journalized in the sleeve 24 and part 25 of the tubular member is a clockwise and counter-clockwise movable shaft 29. The end 30 of the latter terminates adjacent the outer end of sleeve 24. The end 31 of shaft 29 is positioned adjacent the collar 28. The shaft 29 extends outwardly from collar 28 and has fixedly secured thereto a crank handle 32 for the purpose of revolving the shaft in the direction desired. When shaft 29 is to be operated from a motor, the end 30 is attached therewith. The outer end of sleeve 24 is closed by a plug 33 threadedly engaging with the inner face of the sleeve. When shaft 29 is to be driven from a motor, the plug 33 is removed.

Fixedly secured to shaft 31 so as to bodily move therewith is a skeleton cylinder 34 which 45 provides a carrier for the articles to be washed. The cylinder 34 is arranged on shaft 29 between sleeve 24 and part 25 of the tubular member whereby it is maintained in spaced relation with respect to the walls 4, 5 of tank 1. The diameter of cylinder 34 is such whereby it will not depend into the lower portion 8 of the tank, and further will be positioned at a point spaced materially from the lips 9.

The cylinder includes a pair of circular axially apertured spaced parallel oppositely disposed heads 35, 36 of like form, each of which includes a hub 37, a web 38 and a rim 39 of greater thickness than the web. The hub 37 is disposed outwardly and inwardly with respect to the web. The hub 37 is removably connected to the shaft 29 by the holdfast means 40. The rim 39 is formed with a circular row of spaced transverse openings 41 and a series of spaced mortises 41' in its outer edge. The openings 41 in one rim align with the openings 41 in the other rim and a similar arrangement is had with respect to the mortises in the rims.

The heads 35, 36 are connected together by a pair of sets of holders. Each holder consists of a gripper member 42 and a gripper-agitating element 43. The elements 43 of one set are oppositely disposed with respect to the elements 43 of the other set. Each member 42 coacts with an element 43 to provide a frictional gripping means for clamping an article to be washed to a holder.

The members 42 and elements 43 are secured in a manner to be referred to for the purpose of preventing the shifting thereof relative to the heads 35, 36.

Each member 42 is in the form of a cylindrical rod. The rod extends through a pair of aligning openings 41 and is provided with nuts 44 abutting the outer sides of the heads to prevent the shifting of the rod relative to the heads.

Each element 43 is of substantially L-shape in cross section for the major portion of its length to provide an outer arm 45 and an inwardly extending arm 46 of greater width and of less length than the arm 45. The latter extends an equal distance from the ends of arm 46. The arm 45 is formed centrally with an offset stretch portion 47 to provide one of its sides with a concave edge portion 48 and the other of its sides with a convex edge portion 49. The arm 46 centrally of its outer face is provided with a concave groove 50 which registers with the concave edge portion 48. The arm 45 at its concave edge portion, at its edge portions adjacent said concave edge portion and the arm 46 at the outer portion of its outer face is lengthwise serrated as at 51. The parts of the arm 45 which extend from the ends of the arm 46 are apertured as at 52 and seat in a pair of aligning mortises 42. Holdfast devices 53 extend through the openings 52 in the elements 43 and engage 105 in the heads 35, 36 for anchoring said elements and heads together to prevent the former shifting relatively to the latter. The outer faces of the arms 45 of elements 43 are flush with the outer edges of the heads 35, 36.

Each gripper member 42 is arranged in close proximity to but spaced from the outer face of the arm 46 of an element 43 and extends across the groove 50. The stretches of one side of the member 42 which are spaced adjacent the sides of the transverse median of member 42 coact with spaced stretches of the arm 46 which are disposed parallel to the said stretches of member 42 to provide the holder with permanent spaces located adjacent the sides of the transverse median and extending lengthwise of the holder for receiving end portions of the articles to be washed. The inner ends of the spaces are open. The concave edge portions 48, concave grooves 50 and the central stretches of the members 42 coact to 125 provide each holder at its transverse center there-with an enlarged opening to facilitate the entrance of the articles to be washed and suspended from the carrier to the spaces referred to from the inner open ends of the latter. The opposed faces of a member 42 and an element 43 coact to provide a frictional gripping means for detachably clamping in said spaces the end portions of the articles to be washed whereby such articles are removably secured to and suspended against 135 the outer periphery of the carrier. The arms 45 of elements 43 constitute stops to arrest the articles from swinging into the carrier when the articles are suspendingly supported on the outside of the carrier by the gripping means referred to.

The portion 8 of the tank 1 provides a passage 53 for the suspended articles when they are carried around on the revolving of the cylinder and depend from the lower portion of the cylinder.

The wall 3 has apertured offset portions 54 for receiving holdfast devices, not shown, for anchoring to the tank a wringer, not shown.

Each element 43 and the gripper member 42 which is associated therewith provides what may 150

be termed a holder, and under such conditions the carrier is formed with a circumferentially disposed set of spaced holders forming means whereby the articles to be washed are disposed in rows 5 with respect to the carrier.

When using the machine, the tank is filled with water to an extent to have the water level in proximity to the lips 9. Then the articles to be washed are attached to the holder, and in this 10 connection a small fold at an edge of each garment to be washed is passed through the eye at the center of a holder. The article is then shifted to the right or to the left of the holder until the latter is filled. The member 42 and element 43 15 coacts to grip the garments to the holder and the latter functions to suspend the articles upon the outside of the carrier. When attaching the article to a holder, after one holder is filled, the carrier is shifted to position another holder in 20 convenient position to attach the articles thereto. When the articles are suspendingly supported from the carrier, the latter is operated to revolve completely clockwise and then to revolve completely counter-clockwise thus forcing the articles 25 on the outside of the carrier with great resistance through the water in the tank especially through passage 53. In this manner, each article is washed individually.

Each of the elements 43 not only coat with an element 42 to provide a holder and gripping means for an article to be washed, but the arm 46 of such element provides an agitator for the water during the revolving of the carrier.

What I claim is:—

1. A washing machine including a revolute skeleton cylinder constituting a carrier having circumferentially extending parallel spaced holders, each consisting of a gripper member and a gripper-agitating element, said member and element disposed lengthwise and fixedly secured at their ends to the ends of the cylinder, said element having an inwardly extending part disposed radially of the carrier to provide an agitator, said member being arranged in parallel spaced relation to said part but adjacent thereto and coacting with the latter to form a pair of permanent spaces adjacent each side of the transverse median of the holder for the reception of a portion of each of a plurality of articles to be washed, opposed walls of said spaces coacting to provide frictional gripping means for clamping the said portions to the holder to suspend the articles at the outside of the carrier.

2. A washing machine including a revolute skeleton cylinder constituting a carrier having circumferentially extending parallel spaced holders, each consisting of a gripper member and a gripper-agitating element, said member and element disposed lengthwise and fixedly secured at their ends to the ends of the cylinder, said element having an inwardly extending part disposed radially of the carrier to provide an agitator, said member being arranged in parallel spaced relation to said part but adjacent thereto and coacting with the latter to form a pair of permanent spaces arranged adjacent each side of the holder for the reception of a portion of each of a plurality of articles to be washed, the walls of said spaces coacting to provide frictional gripping means for clamping the said portions to the holder to suspend the articles at the outside of the carrier, each of said holders provided with means at the transverse median thereof to form an opening of greater diameter than the width of said spaces to facilitate the entrance of said portions into the spaces from the inner ends of the latter.

3. A washing machine including a revolute skeleton cylinder constituting a carrier having circumferentially extending parallel spaced holders, each consisting of a gripper member and a gripper-agitating element, said member and element disposed lengthwise of the cylinder, said element having an inwardly extending part disposed radially of the carrier to provide an agitator, said member being arranged in parallel spaced relation to said part but adjacent thereto and coacting with the latter to form a gripping means for suspending the articles to be washed on the outside of the carrier, and the said inwardly extending part being formed with a lengthwise serrated portion opposing the gripping member.

4. A washing machine including a revolute skeleton cylinder constituting a carrier having circumferentially extending parallel spaced holders, each consisting of a gripper member and a gripper-agitating element, said member and element disposed lengthwise and fixedly secured at their ends to the ends of the cylinder, said element having an inwardly extending part disposed radially of the carrier to provide an agitator, said member being arranged in parallel spaced relation to said part but adjacent thereto and coacting with the latter to form a pair of permanent spaces arranged adjacent each side of the holder for the reception of a portion of each of a plurality of articles to be washed, the walls of said spaces coacting to provide frictional gripping means for clamping the said portions to the holder to suspend the articles at the outside of the carrier, each of said holders provided with means at the transverse median thereof to form an opening of greater diameter than the width of said spaces to facilitate the entrance of said portions into the spaces from the inner ends of the latter, and the said inwardly extending part being formed with a lengthwise serrated portion opposing the gripper member.

5. A washing machine including a revolute skeleton cylinder constituting a carrier having circumferentially extending parallel spaced holders, each consisting of a gripper member and a gripper-agitating element, said member and element disposed lengthwise and fixedly secured at their ends to the ends of the cylinder, said element having an inwardly extending part disposed radially of the carrier to provide an agitator, said member being arranged in parallel spaced relation to said part but adjacent thereto and coacting with the latter to form a pair of permanent spaces adjacent each side of the transverse median of the holder for the reception of a portion of each of a plurality of articles to be washed, opposed walls of said spaces coacting to provide frictional gripping means for clamping the said portions to the holder to suspend the articles at the outside of the carrier, the said gripper member being arranged inwardly with respect to the outer periphery of the carrier, and the said element having a face portion thereof providing a part of the outer periphery of the carrier.

6. A washing machine including a revolute skeleton cylinder constituting a carrier having circumferentially extending parallel spaced holders, each consisting of a gripper member and a gripper-agitating element, said member and element disposed lengthwise and fixedly secured at their ends to the ends of the cylinder, said element having an inwardly extending part disposed

- radially of the carrier to provide an agitator, said member being arranged in parallel spaced relation to said part but adjacent thereto and co-acting with the latter to form a pair of permanent spaces arranged adjacent each side of the holder for the reception of a portion of each of a plurality of articles to be washed, the walls of said spaces coacting to provide frictional gripping means for clamping the said portions to the holder to suspend the articles at the outside of the carrier, each of said holders provided with means at the transverse median thereof to form an opening of greater diameter than the width of said spaces to facilitate the entrance of said portions into the spaces from the inner ends of the latter, the said gripper member being arranged inwardly with respect to the outer periphery of the carrier, and the said element having a face portion thereof providing a part of the outer periphery of the carrier. 5 80 85
7. A washing machine including a revoluble skeleton cylinder constituting a carrier having circumferentially extending parallel spaced holders, each consisting of a gripper member and a gripper-agitating element, said member and element disposed lengthwise of the cylinder, said element having an inwardly extending part disposed radially of the carrier to provide an agitator, said member being arranged in parallel spaced relation to said part but adjacent thereto and co-acting with the latter to form a gripping means for suspending the articles to be washed on the outside of the carrier, the said inwardly extending part being formed with a lengthwise serrated portion, the said gripper member being arranged inwardly with respect to the outer periphery of the carrier, and the said element having a face portion thereof providing a part of the outer periphery of the carrier. 15 90 95
8. A washing machine including a revoluble skeleton cylinder constituting a carrier having circumferentially extending parallel spaced holders, each consisting of a gripper member and a gripper-agitating element, said member and element disposed lengthwise and fixedly secured at their ends to the ends of the cylinder, said element having an inwardly extending part disposed radially of the carrier to provide an agitator, said member being arranged in parallel spaced relation to said part but adjacent thereto and co-acting with the latter to form a pair of permanent spaces adjacent each side of the transverse median of the holder for the reception of a portion of each of a plurality of articles to be washed, the opposed walls of said spaces coacting to provide frictional gripping means for clamping the said portions to the holder to suspend the articles at the outside of the carrier, an open top and closed bottom tank for receiving a body of water and formed of an upper portion and a lower portion, the latter being of less area than the former and providing a passage for the suspended parts of said articles, said carrier being arranged in said upper portion, spaced from the top of the latter and spaced above said lower portion, operable means extending across the tank and connected to the carrier for revolving the latter, and a hinged closure for the open top of the tank. 40 100 105
9. A washing machine including a revoluble cylinder formed of a skeleton body closed at each end and constituting a carrier having circumferentially extending parallel spaced lengthwise disposed holders, each consisting of a gripper member of circular cross section and a gripper-agitating element of substantially L-shaped cross section, said member and element being arranged in parallel spaced relation for receiving and frictionally clamping therebetween articles to be washed, said member having its ends fixedly secured to, extending into and arranged in close proximity to the edges of the ends of the cylinder, said element having its ends fixedly secured to and seated in the end edges of the cylinder ends, extending inwardly into the cylinder with respect to said member and having one face thereof permanently providing an outer peripheral portion of said body. 45 110 115
10. A washing machine including a revoluble cylinder formed of a skeleton body closed at each end and constituting a carrier having circumferentially extending parallel spaced lengthwise disposed holders, each consisting of a gripper member of circular cross section and a gripper-agitating element of substantially L-shaped cross section, said member and element being arranged in parallel spaced relation for receiving and frictionally clamping therebetween articles to be washed, said member having its ends fixedly secured to, extending into and arranged in close proximity to the edges of the ends of the cylinder, said element having its ends fixedly secured to and seated in the end edges of the cylinder ends, extending inwardly into the cylinder with respect to said member and having one face thereof permanently providing an outer peripheral portion of said body, the cross sectional area of said members being materially less than the cross sectional area of each of said elements. 50 120 125
11. A washing machine including a revoluble cylinder formed of a skeleton body closed at each end and constituting a carrier having circumferentially extending parallel spaced lengthwise disposed holders, each consisting of a gripper member of circular cross section and a gripper-agitating element of substantially L-shaped cross section, said member and element being arranged in parallel spaced relation for receiving and frictionally clamping therebetween articles to be washed, said member having its ends fixedly secured to, extending into and arranged in close proximity to the edges of the ends of the cylinder, said element having its ends fixedly secured to and seated in the end edges of the cylinder ends, extending inwardly into the cylinder with respect to said member and having one face thereof permanently providing an outer peripheral portion of said body, and said element having that face opposing said member being formed centrally thereof with a transversely extending concave groove. 55 130 135
12. A washing machine comprising an open top tank formed of an upper and a lower portion, the latter providing a passage for articles being washed, a revoluble closed end and open body carrier formed with parallel spaced lengthwise extending permanently fixed combined holders and agitators for suspending the articles to be washed upon the outer face of the body of the carrier and for holding said articles in depending position from the bottom of the carrier when the articles are traveling through said passage, said carrier being positioned in said upper portion, the top of the carrier being located below the top and the bottom of the carrier being located above the lower end of said upper portion, and means extending through said upper portion and carrier for revolving the latter. 60 140 145
